UNITED STATES PATENT OFFICE.

GEORGE A. LAUBERSHEIMER, OF LOS ANGELES, CALIFORNIA.

REAR INDICATOR FOR VEHICLES.

1,125,030.

Specification of Letters Patent. Patented Jan. 12, 1915.

Application filed November 24, 1913. Serial No. 802,712.

To all whom it may concern:

Be it known that I, GEORGE A. LAUBERSHEIMER, a citizen of the United States, residing at the city of Los Angeles, in the county of Los Angeles and State of California, have invented new and useful Improvements in Rear Indicators for Vehicles, of which the following is a specification.

The main object of my invention is to provide an automobile or other vehicle with mechanism that can be quickly set to indicate to a vehicle following the direction that the leading vehicle will take at a street or other crossing.

15 In the drawings forming a part of this application:

Figure 1 is a face view or view shown to a following vehicle of the indicating portion of the mechanism with parts of the operating mechanism shown in full and in dotted lines. Fig. 2 is a section on the line 2—2 of Fig. 1. Fig. 3 is a diagrammatic view.

I will describe my device as applied to an automobile.

25 In the drawings 5 is a box or case in which is pivotally mounted, in bearings 6, a semaphore arm or bar 7 which projects through a slot 8 in the top of the case.

30 Bar 7 has a slot 9 extending longitudinally therethrough near its mounting and on the top thereof is a reflector 10 in the sides of which are mounted transparent colored panels 11 which are preferably green.

35 Mounted on the top of bar 7 is an incandescent electric lamp 12 which is connected by wiring 13 with the lighting system of the machine.

40 Mounted within box 5 preferably at each end thereof are magnets 14 and 15 which are preferably solenoid magnets having a common plunger 16 which passes through bearings 17 and 18 secured to the box.

45 Plunger 16 carries a pin 19 which projects through slot 9 in bar 7.

Coiled around plunger 16 between bar 7 and bearing 17 is a spring 20 and a second spring 21 is coiled around the plunger between bar 7 and bearing 18. These springs 50 normally hold bar 7 in a vertical position.

Secured to the top of box 5 is a vertical plate 22 which is provided with a central aperture 23 in which is mounted a transparent colored plate 24 which is in line with lamp 12 when the machine is traveling along the street not near a crossing. Plate 24 is

preferably red and in conjunction with lamp 12 operates as a tail light at night.

One side of magnets 14 and 15 is connected to one pole of battery 25. The other pole of battery 25 is connected to contacts 26 and 27. The other side of magnet 14 is connected to switch 28. The other side of magnet 15 is connected to switch 29.

60 Contacts 26 and 27 and switches 28 and 29 are placed at a point convenient of access to the driver, preferably the dash board (not shown).

65 With the parts herein described suitably mounted in and on the automobile should the driver desire to turn to the right at a corner he closes switch 28 just before he gets to the turning point thereby energizing magnet 14 which draws the top of bar 7 to the right thus indicating that the vehicle will turn to the right at the next corner. After turning the corner he opens the switch and spring 20 returns bar 7 to its normal position.

70 If he desires to turn to the left he closes switch 29 which draws the top of bar 7 to the left thus indicating that the vehicle will turn to the left at the next corner. After turning the corner he opens the switch and spring 21 returns bar 7 to its normal position. By using lamp 12 as a tail light 75 as well as a signal light for turning, the attention of the driver of the following vehicle is instantly attracted to the leading vehicle when the driver indicates his intention to turn, because first the red tail light disappears and at one or the other side of the accustomed place for the tail-light appears a clear light, which indicates that the leading machine will turn to the right or left at the next corner.

80 If desired plate 22 could be omitted but in such case the device could not be used as a tail light and would not be as desirable as with the plate.

85 Having described my invention what I claim is:

1. A signaling device for vehicles comprising a casing secured upon the vehicle; a semaphore arm pivotally mounted therein and normally projecting vertically above the top thereof; an electric lamp on the top of said arm; a plate having an aperture therein secured to said casing and on a vertical line with the semaphore arm, said aperture being on a horizontal line with the lamp; a transparent colored closure for said aperture; two magnets operatively connected to the semaphore arm whereby the top thereof is 90 95 100 105 110

- 5 moved to the right or left of the vertical line whenever one or the other of said magnets is energized; and means to energize one or the other of said magnets when desired.
- 5 2. A signaling device for vehicles comprising a casing secured upon the vehicle; a semaphore arm pivotally mounted therein and normally projecting vertically above the top thereof; an electric lamp on the top of 10 said arm; a reflector secured upon the top of said arm at the back of said lamp when viewed from the rear of the machine; a plate having an aperture therein secured to said casing and on a vertical line with the semaphore arm, said aperture being on a hori- 15 zontal line with the lamp; a transparent colored closure for said aperture; two magnets operatively connected to the semaphore arm whereby the top thereof is moved to the right or left of the vertical line whenever 20 one or the other of said magnets is energized; and means to energize one or the other of said magnets when desired.

In witness that I claim the foregoing I have hereunto subscribed my name this 19th 25 day of November, 1913.

GEO. A. LAUBERSHEIMER.

Witnesses:

G. E. HARRIS,
FRANK WATERFIELD.
